ELECTRO-MECHANICAL POWER UNIT
 Henry A. Sherwood, Short Hills, N.J., assignor to U.S.
 Servicator Corporation, Plainview, N.Y., a corporation
 of Delaware
 Filed Jan. 17, 1961, Ser. No. 33,346
 5 Claims. (Cl. 307—141)

The present invention relates to power units or prime movers, and particularly to an electro-mechanical prime mover or motor which is cyclically operable and has its intermittent motion translated to effect a predetermined, timed action or series of timed actions.

Power units of the type to which the present invention relates have been suggested heretofore but so far as can be determined they have proved to be impracticable and unreliable because of variables which exist or develop in the inter-relation of their electrical and mechanical functions. The present invention overcomes this undesirable defect of the prior art by providing a motor constructed to assure its proper and accurate functioning, which is attained by the provision of means for establishing a definite inter-relation of all of its operating parts to effect a fixed sequence of action of those parts.

To this end, the present invention in its broad aspects contemplates a power unit having drive and driven means connected by power transmission means, wherein the drive means comprises a bi-metallic element mounted to move in response to the application of heat thereto, and means for applying the heat intermittently to effect a cyclic movement of the bi-metallic element upon its being successively heated and then allowed to cool during each cycle.

More specifically, the invention provides a bi-metallic element surrounded by an electric resistance coil arranged in an electric circuit which is opened and closed by a rockable over-center spring switch, the switch in turn being actuated by the movement of the bi-metallic element to effect its rocking from "on" to "off" position, and vice versa. The bi-metallic element is equipped with a pawl which engages with the teeth on a ratchet wheel so that when the element moves in response to its being heated by the resistance coil, its movement is translated through the pawl to turn the ratchet wheel. An arm secured to the bi-metallic element and movable with it serves as an anchor for one end of the switch spring, and when the element has moved sufficiently to rotate the ratchet wheel through a distance equal to the pitch of the tooth engaged by the pawl, the arm to which the spring is anchored will have moved a distance sufficient to carry the spring beyond center, whereupon it exerts a force which rocks the switch to break the electric circuit and allow the bi-metallic element to cool and return to its original position. In so doing, the spring is returned past center, whereupon it rocks the switch back to its original position to reestablish the electric contact and open the circuit and commence to next cycle of operation.

It is a prime feature of the invention that the power unit achieves its reliability from the concept of an inter-related adjustability of its operating parts. Thus, the bi-metallic element is adjustable to place it under tension or pre-load it beyond the point where it is affected by the temperature of the atmosphere. Such adjustment determines the initial positions of the element, the driving pawl, the ratchet wheel and the switch spring anchoring arm; and in this condition of the parts the switch spring is accurately located on the arm, the "on" and "off" positions of the switch are adjusted to proper locations, and a holding pawl is adjusted relative to the

2

teeth of the ratchet wheel, its function being to prevent rotation of the wheel in a direction reverse to that in which it is being driven.

Other features of the invention need not be enumerated, since they will be obvious to anyone skilled in the art after reading the following detailed description of the embodiment invention shown in the drawings.

In the accompanying drawings, the invention has been shown merely by way of example and in preferred form, and obviously many variations and modifications may be made therein which will still be comprised within its spirit. It is to be understood, therefore, that the invention is not limited to any specific form or embodiment except insofar as such limitations are set forth in the appended claims.

Referring to the drawings,

FIG. 1 is a side elevation, showing the working structure of the present invention;

FIG. 2 is a view similar to FIG. 1, showing the parts in a different position; and

FIG. 3 is a modified form of a part of the mechanism shown in FIGS. 1 and 2.

As already stated, the device of the present invention is a very simplified form of electro-mechanical power unit comprising a drive means 10, a driven means 11 and power transmission means 12 connecting the drive means to the driven means. The parts comprising the drive means 10 are mounted on a support 13 to which they are secured in any suitable manner such as by screws entering from behind the support 13 and therefore not visible in the drawing. A block of insulating material 15 is secured to the upper part of the support 13 and anchored to the block 15, as by screws 16, is one leg 17 of a bi-metallic element 18, the other and longer leg 19 of the element 18 depending for a considerable distance below the block 15 in a position to swing relative to the fixed leg 17. Also secured to the block 15, one at each side thereof, are a pair of arms 20 and 21 which act as stops and may be identified as an "on" stop 20 and an "off" stop 21.

A bracket 22 is secured to the support 13 below and in spaced-apart relation to the block 15, and at its lower forward edge the bracket 22 is formed with an arm 23 bent outwardly relatively to the support 13 at a right angle to the bracket 22 and drilled and threaded to accommodate an adjusting screw 24, a lock nut 25 being provided to hold the screw 24 in any adjusted position. The free end 26 of the screw 24 extending beyond the arm 23 is arranged to engage the leg 19 of the bi-metallic element 18 near its free end for the purpose of pre-loading or placing the leg 19 under a predetermined tension for a purpose to be explained more fully hereinafter. Secured to the leg 19 of the bi-metallic element 18 is an arm 27 arranged to extend rearwardly or toward and alongside but out of contact with the bracket 22. As will be observed, the bottom edge of the arm 27, from its free end and throughout approximately one-half of its length, is formed with serrations 28.

The upper edge of the bracket 22 is formed with a V-shaped notch 29 adapted to serve as a pivot seat for a switch arm 30. As shown in FIG. 1, the switch arm 30 extends from the notch 29 upwardly between the arms 20 and 21 and its upper end engages the under surface of a flexible spring contact 31 which is secured to or made as a part of an electric conductor 35 secured to the insulated block 15 as by a screw 14. The switch arm 30 is held on the V-shaped seat 29 by a tension spring 32 having one end 33 engaged in an aperture 34 formed in the switch arms and its lower hook-shaped end 34a engaged in one of the serrations 28 on the arm 27, the spring being under slight tension to exert a downward pull on

the switch arm 30. The arrangement is what is commonly known as an over-center spring switch.

As already stated, the contact 31 is secured to the conductor 35 fastened to the block 15, and the conductor 35 is in contact with an electric wire 36 also secured by the screw 14 and comprising one lead from a source of electric power. A second electric wire 37 leading from the source of electric power is connected to an electrical resistance coil 38 surrounding the leg 19 of the bi-metallic element 18, the opposite or lower end of the resistance coil being soldered or otherwise electrically connected as at 39 to the leg 19 of the bi-metallic element 18. Thus, an electric circuit is established whereby electricity is conducted by the lead wire 36 to the conductor 35, through the contact 31 to the switch arm 30, then through the spring 32 to the arm 27 and the leg 19 of the bi-metallic element 18 through the resistance coil 38 and the lead wire 37.

It may be noted that a second conductor 35a is secured to the block 15. In the present instance the second conductor is not hooked into the electric circuit and is, therefore, "dead." If, for some reason, the "on" and "off" positions of the switch 30 were to be reversed, the lead wire 36 would be connected to the conductor 35a instead of to the conductor 35.

The operation of the power or drive means as thus far described is as follows: With the parts in the position shown in FIG. 1, the leg 19 of the bi-metallic element 18 rests against the free end of the adjusting screw 24, the adjusting screw having been set to move the leg 19 counterclockwise under tension to a predetermined extent equivalent to the amount of movement of the leg 19 which would be effected by the application of a certain amount of heat, say 150° F. This would be a minimum preloading of the leg 19 in order to set it beyond the point where it would be affected by the temperature of the atmosphere. When the leg 19 has been adjusted as just stated, carrying the arm 27 with it, the lower end of the spring 32 is then located in that serration 28 which lies in the vertical plane of the opening 34 in the switch arm 30, and the spring holds the switch arm under tension against the "on" stop 20 and in engagement with the electric contact 31. Thus, in this position of the parts, electric current will flow through the circuit already described and cause the resistance coil 38 to heat the leg 19 of the bi-metallic element 18. As the heat thus applied to the leg 19 rises above 150° F. the leg 19 swings to the right or counterclockwise until it reaches the position shown in FIG. 2. As a result of such movement of the leg 19, the arm 27 is also moved in the same direction and carries the lower end of the spring 32 with it until it reaches that position (the position shown in FIG. 2) at which point the pull of the spring 32 on the switch arm 30 causes the latter to rock with a snap action to the position shown in FIG. 2 where it comes to rest against the "off" stop 21. This movement of the switch arm 30 sweeps it out of engagement with the contact 31, breaking the electric circuit, whereupon the application of heat to the leg 19 ceases and the latter cools off. In cooling, the leg 19 gradually resumes its initial position, moving back into contact with the end of the adjusting screw 24. In so moving, it carries the arm 27 and the lower end of the spring 32 with it and as it comes to rest against the adjusting screw 24, the spring 32 has been moved far enough to exert a pull to the left causing the switch arm 30 to rock back against the "on" stop 20 and into engagement with the electric contact 31. This re-establishes the electric circuit and the operation of the parts due to the application of heat to the leg 19 as just described is repeated. Such intermittent operation of the power unit continues for so long a time as electric current is available to flow through the circuit from the wires 36 and 37.

The driven means is, in effect, an accumulator, and in the present instance it is shown in its simplest form as

comprising a single ratchet wheel 40 formed on its periphery with teeth 41, the ratchet wheel 40 being mounted for rotation on a stud 42 secured to the support 13. Power transmission means in the form of a pawl 43 is secured at one end to the leg 19 of the bi-metallic element 18 as by a rivet 44. The pawl 43 is flexible, being made of material such as spring steel, and has its free end bent to form a nose 45 adapted to engage between the teeth 41 on the ratchet wheel 40. The spacing 10 of the teeth 41 is such that each movement of the leg 19 during the application of heat thereto will move the ratchet wheel 40 a distance equal to the pitch of one tooth, and when the leg 19 returns to its initial position upon cooling, the pawl 43 is carried with it and the nose 45 thereof rides over and drops in front of the 15 succeeding tooth on the ratchet wheel 40.

A holding pawl 46 is adjustably mounted by a slot and screw connection 47 in fixed position on the support 13 so that the bent over free end of nose 48 of the pawl 46 20 engages behind one of the teeth 41 on the ratchet wheel 49. Each time the ratchet wheel 40 is moved a distance of one tooth by the power transmission pawl 43, the nose 48 of the pawl 46 rides over one tooth 41 and drops behind it to prevent reverse rotation of the ratchet wheel 25 40 when the pawl 43 is carried to the left upon the cooling of the leg 19 of the bi-metallic element 18. Thus, during each heating cycle of the power unit, the ratchet wheel 40 is rotated a distance equal to the pitch of one tooth and held in that position.

30 In the embodiment of the invention shown in the drawings, a cam 50 is carried by or mounted to rotate with the ratchet wheel 40 to actuate a lever 51 pivotally mounted on the support 13 approximately midway of its length, as at 52. One arm 53 of the lever 51 is held in firm engagement with the periphery of the cam 50 by a spring 54. One end 55 of the spring 54 is hooked into an aperture 56 formed in the arm 57 of the lever 51 and the opposite end thereof is hooked over a pin 58 fixed in the support 13, placing the spring under a slight tension. In operation, 40 with the parts in the positions shown in FIG. 1, as the ratchet wheel 40 rotates intermittently the cam 50 is rotated therewith and the eccentric portion 59a of its periphery rocks the lever 51 step by step to the dotted line position shown in FIG. 2. Upon reaching that position, the arm 57 of the lever 51 will have been rocked clockwise, 45 against the action of the spring 54 to a position where it engages and actuates an electric switch 60 secured to the support 13 by means of screws 61 (see FIG. 2). When the ratchet wheel 40 is next moved by the pawl 43, the eccentric portion 59a of the cam 50 will move out of engagement with end of the arm 53 of the lever 51 and allow the latter to be rocked counterclockwise to the position shown in FIG. 1 (and by the full lines in FIG. 2) by the relaxation of the spring 54. Continued rotation of the ratchet wheel 40 will be idle according to the embodiment of the 50 invention shown in FIGS. 1 and 2, with the arm 53 riding on the concentric portion 59 of the cam until such time as the eccentric portion 59a reengages the arm 53.

While the single cam 50 shown in FIGS. 1 and 2 may be desirable in certain instances, there may be other instances where it is not desirable to have an idle rotation of the ratchet wheel 40. Thus, the modification shown in FIG. 3 may be employed wherein the cam is formed with a second eccentric peripheral portion 59b, whereby as the eccentric portion 59a moves away from the arm 53 of the lever 51 and allows the latter to be rocked clockwise, the arm 53 drops into engagement immediately with the second eccentric portion 59b of the cam 50. Thus, with the modification shown in FIG. 3 one complete rotation of the ratchet wheel 40 effects two rocking movements of the lever 51 and two actuations of the switch 60.

The foregoing sets forth the details of an extremely simple and inexpensive power unit or prime mover, the reliability of which is achieved by the adjustability of its 75 operating parts. Thus, the cycling of the bi-metallic leg

19 is made to occur outside the temperature of the atmosphere, i.e., 150° F. or higher, by adjusting the screw 24 to pre-load the leg 19. Such pre-loading brings the driving pawl 43, ratchet wheel 40 and arm 27, into definite initial positions. With the establishment of the initial position of the ratchet wheel 40, the holding pawl 46 can be adjusted by means of the slot and screw mounting to locate the nose 48 of the pawl accurately with relation to a tooth 41 on the ratchet wheel, and the lower end of the spring 34a can be accurately hooked in the proper serration 28 on the arm 27. Furthermore, to assure the proper action of the over-center switch 30, its time of movement away from the "on" stop 20 must be after the leg 19 through the driving pawl 43 has moved the ratchet wheel 40 the full distance equal to the pitch of one tooth 41 and the nose 48 of the holding pawl 46 has dropped behind a tooth 41 on the ratchet wheel. On the other hand, the movement of the switch 30 away from the "off" stop 21 must be after the leg 19 has cooled and returned completely to rest against the adjusting screw 24 and the driving pawl has dropped in front of the succeeding tooth 41. In the embodiment of the invention shown in the drawings the stops 20 and 21 may be independently adjusted by being bent inward or outward relative to the fixed pivot point, the V-shaped notch 29, of the switch 30 to obtain the proper timing in relation to the extent of movement of the arm 27. If desired, of course each stop 20, 21 could be equipped with an adjusting screw such as the screw 24 to accomplish the same purpose, but that would add to the cost and might involve a problem of accessibility in small, compact units.

It is also pointed out that reliability in the functioning of the power unit 10 is aided by the utilization of the flexible spring form of electric contact 31, which provides for a wiping engagement of the switch arm 30 therewith and thus assures the making of a good contact. In connection with the matter of reliability it has also been found that to insure proper control the driving cycle of the power unit should be taken during the heating phase of the bimetallic leg 19 rather than during the cooling phase.

As already stated, the invention has been shown in the drawings in its simplest form and as actuating an electric switch 60 which, in turn, may effect the operation of any device to which it is connected. However, instead of rocking a lever the ratchet wheel may operate a multiple gear arrangement whereby the movement of the ratchet wheel 40 is translated to effect the operation of other mechanism after less than one complete rotation of the ratchet wheel 40 or after many complete rotations thereof, dispensing entirely with the use of a cam or cams to translate the motion of the ratchet wheel. Other mechanisms and their modes of operation will occur to persons skilled in the art and it is not the purpose of this disclosure to set forth in detail all of the forms of mechanisms with which the power unit may be employed. It is pointed out, however, that the invention provides an electromechanical motor usable to drive means for accomplishing timed kinetic actions, the motor being cycled by a switch controlled by the operation of the motor and whose cyclic operations are accumulated to produce a predetermined result. By way of example, one use could be to connect the wires 36 and 37 to the ignition of an automobile to give notice (as by the ejection of printed cards from a casing) of the different times when the automobile should be serviced for oil change, ignition inspection, etc. The notice will be according to the length of time that the motor has operated, rather than being based on the speedometer reading or mere lapse of time since the previous servicing.

It should be mentioned that the accurate form of prime mover according to the present invention will find an almost unlimited number of uses in many fields. It has been shown and described herein merely in a simplified form, utilizing a cam action to effect the actuation of an electric switch, which in turn may set into motion any

one of a number of conceivable devices for performing a given function. But it has a usefulness whenever and wherever it is desired to perform some function or series of functions under conditions of definite timing. Its use in connection with a privately owned automobile has been mentioned merely by way of example, for its use extends to installations for other purposes in the automotive field such as taxis, rental cars, buses, truck fleets, etc., or in the field of motor boats, aviation, agriculture equipment, etc., in civil government operations and the armed services; institutions such as hospitals; and many industrial operations. In short, there is a need in all these fields for a reliable, accurate prime mover for effecting timed functions and the present invention supplies that need in an extremely simple and inexpensive mechanism.

Having thus described my invention, what I claim is:

1. A power unit including, in combination, a support, a bi-metallic strip mounted with one end fixed to the support and the opposite end free for swinging movement relative to said fixed end, a ratchet wheel mounted on said support for rotation about its axis, a pawl means connected to said element near the free end thereof with an end of said pawl means engaging a tooth on said ratchet wheel, an electric circuit, an electric resistance coil connected in said circuit and arranged to surround a major portion of said bi-metallic element for applying heat thereto, a switch arranged in said electric circuit and mounted for movement to open and close the circuit, and a connection between the free end of the bi-metallic element and said switch to effect the movement of the switch in response to the swinging movements of the free end of said element, adjustable means operable to predetermine the minimum degree of heat required to effect initial movement of the bi-metallic element, said support including a bracket, a switch arm pivotally seated on said bracket, an anchor arm connected to and extending from the bi-metallic element toward said bracket in a position below the switch arm, and a vertically disposed spring connected at one end to said switch arm and at its other end to said anchor arm, whereby movement of the bi-metallic arm carries with it the anchor arm and the end of the spring connected thereto and effects an off-center pull on the switch arm to rock it on its pivot.

2. A power unit including, in combination, a support, a bi-metallic strip mounted with one end fixed to the support and the opposite end free for swinging movement relative to said fixed end, a ratchet wheel mounted on said support for rotation about its axis, a pawl means connected to said element near the free end thereof with an end of said pawl means engaging a tooth on said ratchet wheel, an electric circuit, an electric resistance coil connected in said circuit and arranged to surround a major portion of said bi-metallic element for applying heat thereto, a switch arranged in said electric circuit and mounted for movement to open and close the circuit, and a connection between the free end of the bi-metallic element and said switch to effect the movement of the switch in response to the swinging movements of the free end of said element adjustable means operable to predetermine the minimum degree of heat required to effect initial movement of the bi-metallic element, a mechanism adapted for periodic timed operation, and actuating means operated by the movement of the ratchet wheel for effecting the timed operation of said mechanism.

3. A combination according to claim 2, wherein the switch arm is rockable from circuit opening to circuit closing positions with heat being applied to said bi-metallic element when said switch arm is in circuit closing position, said pawl means advancing said ratchet wheel during intervals when heat is applied to said bi-metallic element.

4. A combination according to claim 1, wherein the anchor arm is formed with a plurality of spring holding elements whereby the spring may be selectively connected to any one of them to assure its accurate vertical disposition.

5. A combination according to claim 1, wherein the switch arm is rockable from circuit opening to circuit closing positions, and vice versa, and including and adjustable stop means for accurately locating the switch arm in each position.
